(57) CLAIM

The massage chair, as shown and described.

DESCRIPTION

FIG. 1 is a front side view of the design according to the invention.

FIG. 2 is a back side view of the design according to the invention.

FIG. 3 is a top side view of the design according to the invention.

FIG. 4 is a bottom side view of the design according to the invention.

FIG. 5 is a left side view of the design according to the invention. The right side view is exactly the same as the left side view.

FIG. 6 is a perspective view of the design according to the invention; and,

FIG. 7 is another perspective view of the design according to the invention.

The broken lines indicate the environment related to the claimed design. They form no part of the claimed design.

1 Claim, 7 Drawing Sheets

FIG. 1

FIG. 2FIG. 3
